(57) **CLAIM**

The ornamental design for a camera, as shown and described.

DESCRIPTION

FIG. 1 is a front, top and right side perspective view of a camera showing our new design;

FIG. 2 is a front, bottom, and left side perspective view thereof;

FIG. 3 is a rear, top, and left side perspective view thereof;

FIG. 4 is a rear, bottom, and right side perspective view thereof;

FIG. 5 is a front elevational view thereof;

FIG. 6 is a rear elevational view thereof;

FIG. 7 is a right side elevational view thereof;

FIG. 8 is a left side elevational view thereof;

FIG. 9 is a top plan view thereof; and,

FIG. 10 is a bottom plan view thereof.

The broken lines in the drawings showing portions of the camera are included for the purpose of illustrating environmental structure and form no part of the claimed design.
